[57] CLAIM

The ornamental design for a converter housing, as shown and described.

DESCRIPTION

FIG. 1 is a top plan view of the converter housing showing our new design, the bottom plan and rear elevational views being mirror images thereof;

FIG. 2 is a front elevational view thereof;

FIG. 3 is a right side elevational view thereof;

FIG. 4 is a left side elevational view thereof;

FIG. 5 is a perspective view of the converter housing as seen from the front upper left.
